TOOTHBRUSH GUARD AND SUPPORT

George T. Gallo, 15 Cataldo Drive,
Revere, Mass. 02151

Filed Mar. 27, 1975, Ser. No. 562,429

Term of patent 14 years

Int. Cl. D4—02

U.S. Cl. D4—24

FIG. 1

FIG. 3

FIG. 4

FIG. 5

FIG. 6

FIG. 7

FIG. 2

FIG. 1 is an elevation of a toothbrush guard and support supporting a toothbrush in a reclining position;

FIG. 2 is an elevation of a toothbrush guard and support supporting a toothbrush vertically in a toothbrush holder;

FIG. 3 is a front elevational view of a toothbrush guard and support shown on an enlarged scale;

FIG. 4 is a right side elevational view, the rear of the left side being a mirror image thereof;

FIG. 5 is a rear elevational view thereof;

FIG. 6 is a top plan view thereof; and

FIG. 7 is a bottom plan view thereof.

The broken line disclosures of a toothbrush and table top in FIG. 1 and of a toothbrush and toothbrush holder in FIG. 2 are for illustrative purposes only and form no part of the claimed design.

I claim:

The ornamental design for a toothbrush guard and support, as shown and described.
